DISTILLATION OF TAR

Gregory Edward McCloskey, South Orange, N. J.,
assignor to The Barrett Company, New York,
N. Y., a corporation of New Jersey

Application August 6, 1930, Serial No. 473,329

5 Claims. (Cl. 202—30)

This invention relates to the distillation of tar. More particularly it relates to the distillation of tar in a current of hot gases in which heat for the distillation is supplied by the sensible heat of hot combustible gases, and additional heat is supplied by combustion of at least a portion of the combustible ingredients in the gases. Fresh hot coal distillation gases may be used, for example, and by partial or complete combustion of the gases heat is supplied to the still in addition to the heat of the fresh hot gases. The invention includes both the process and apparatus for carrying it out.

Coal tar such as coke oven tar or gas house tar and water gas tar comprise constituents which are readily decomposed at high temperatures and by distillation according to the usual methods more or less decomposition of these constituents takes place. Such decomposition decreases the yield of distillate oil obtained and increases the free carbon content of the pitch produced. Such decomposition also results in the generation of fuel gases. The distillation of this invention may be so carried out as to increase the carbon content of the pitch produced by keeping the tar or the resulting pitch at the high temperature maintained in the still for a prolonged period of time. Or by regulating the distillation so that the tar and pitch remain in the still but a short length of time, for example several seconds, and by spraying the tar in the still in the form of a fine intense spray whereby a large surface of the tar is exposed to the action of the gases so that rapid distillation is effected, the gases are quickly cooled to a temperature approaching the temperature of the tar, and high oil yields will be obtained. The process is advantageously controlled so that the tar is distilled to obtain high oil yields and a pitch of high melting point, for example 350 or 400° F. or higher.

The invention will be described more particularly as applied to the distillation of tar at a coke oven plant by conveying the coke oven gases resulting from the distillation of the coal to the still, preferably without substantial heat loss. By mixing a regulated amount of air with the hot gases and igniting the gases so that at least a part of the combustible constituents in the gases are burned the temperature of the gases in the still and the heat available for distillation are increased.

Fresh hot coke oven gases and other coal distillation gases comprise light oil vapors and vapors of carbolic and creosote oils, etc. finely

suspended particles of pitch and coal or coke and combustible gases, viz. methane, etc. By mixing air with these gases in a regulated amount and igniting the gases, all or a part of these combustible constituents can be burned before the gases come in contact with the tar spray. The resulting gases contain carbon dioxide in increased amount and may contain combustible constituents. The percentage of air mixed with the gases may be so regulated that only a small portion or a larger portion or substantially all of the condensable constituents, as desired, are burned before the gases enter the still. The air content of the gases is advantageously so regulated that there is little or no oxygen in the gases after combustion, although the oxygen content may intentionally be so regulated that these gases contain oxygen in sufficient amount to cause a partial burning of the tar or pitch in the still for the purpose of still further raising the temperature of the gases.

The amount of combustion may be so controlled that the gases first contact with the tar or pitch at a temperature of 1000° C. or 1200° C. or higher. The still is filled with a fine intense spray of tar or the pitch resulting from distillation of the tar. The walls of the still are continually washed with the tar or pitch to prevent the accumulation of pitch or coke thereon. The spray is advantageously produced by rapidly rotating in the still one or more members of generally cylindrical contour at a high rate of speed in such a way that they dip to but a slight extent into a body of the tar or pitch maintained in the bottom of the still and throw a fine intense spray of tar or pitch into the gases which fills the entire vapor space of the still. A roll with a smooth cylindrical surface or a grooved or fluted roll or a plurality of discs closely spaced on a shaft may be employed for this purpose. With a smooth cylindrical roll twelve inches in diameter a speed of 900-1200 R. P. M. is sufficient to throw a fine intense spray of tar and fill a still of several square feet cross-section.

The tar to be distilled may be raw tar containing a small percentage of moisture or it may be dehydrated tar or a partially distilled tar or semi-pitch. The tar may be coke oven tar, gas house tar, low temperature carbonization tar, water gas tar, etc. Tar is used generally herein to include all grades of tar.

The tar may be fed into the still at the same end at which the hot gases enter so that the gases and tar flow thru the still in a generally

concurrent direction of the tar and gases may enter opposite ends of the still and flow thru the still in a generally countercurrent direction. Where pitch of high carbon content is desired, 5 countercurrent flow is ordinarily advantageous. Where countercurrent flow is employed the pitch will leave the still at a higher temperature, the free carbon content will be somewhat higher and the oils remaining in the pitch will be of 10 somewhat higher boiling range than is the case with countercurrent flow.

The spray of tar and pitch maintained in the still is so intense that when the gases entering the still contain fine particles of pitch or coke, 15 etc. in suspension such as are present in coke oven gases, for example, these suspended particles will be removed from the gases in the still and the gases leaving the still will be substantially free from suspended particles except 20 for particles of the spray which may be carried forward with the gases. Such entrained particles may be removed in a settling tower or by baffles or by electrical precipitation, etc., and such removal is advantageously carried out 25 at a high temperature so that upon subsequent condensation clean oils will be produced.

The gases enter the still at a temperature sufficiently high to coke the tar. The fine intense spray of tar promotes rapid distillation 30 and the gases are so rapidly cooled that coking of the tar is reduced to a negligible amount; the gases usually leave the still at such a low temperature that they may be brought into further direct contact with tar without any 35 substantial decomposition of the tar. In order to utilize the heat in the gases leaving the still it is ordinarily advantageous to partially distill the tar, using this heat, before the tar enters the still and is brought into direct contact with 40 the high temperature gases. For this purpose a tar spray free from particles of such small dimension that they will be carried forward in the gases may be employed and this spraying may be such as to remove or aid in the removal 45 of entrained spray particles from the gases leaving the still. The gases may advantageously be passed from the still up thru a baffle tower into which the tar is sprayed and the tar in washing down over the baffles is distilled and 50 removes entrained particles of fine spray from the gases so that the gases leaving the baffle tower are substantially free from entrained particles. Tar which has been partially distilled in this tower is then fed directly into the 55 high temperature still for distillation to pitch.

In carrying out the distillation in combination with a coke oven battery it is advantageous to maintain the still under a partial vacuum in 60 order to prevent loss thru leakage of coke oven gases from the still and to prevent contamination of the air with such gases. Although a higher vacuum may be employed to aid in the distillation, a low vacuum of an inch or two of 65 water is sufficient to prevent loss of gases thru leakage from the still. When the still is operated under a vacuum, the air for combustion of the gases is advantageously admitted into the gas main thru one or more apertures which are 70 preferably equipped with valve means to control the amount of air blended with the gases. The process may, however, be carried out under pressure; that is, the pressure within the combustion chamber, the distillation chamber, etc. 75 may be above that of the atmosphere, air or

other oxygen-containing gas being fed to the system under a suitable higher pressure.

The gases resulting from the combustion which may, and which generally will, contain a considerable percentage of combustible constituents which are not burned, will then pass thru the still to effect the high temperature distillation and will then pass on thru a settling chamber or baffling means, etc. for removal of entrained spray and preferably for further distillation also, and then to condensers. The exhauster is advantageously situated beyond the condensers. After passing thru the exhauster the gases may pass thru suitable means for the recovery of ammonia and light oil, etc.

A separate chamber may be provided for the combustion of the gases and in this case it is advantageously situated adjacent to the still so that the gases enter the still without any appreciable loss of heat. On the other hand, the combustion may take place within the still or partially in the gas conveying pipe and partially in the still or it may be effected merely in the pipe which conveys the gases to the still. This pipe and the still, etc. are advantageously 25 heavily insulated.

Safety devices such as wire screens, explosion doors, etc. may be provided.

In the drawings the invention will be described more particularly as applied to the distillation 30 of coke oven tar at a coke oven battery but it is intended and is to be understood that the invention is not limited thereto. Other tar may be distilled and other hot combustible gases may be employed for the distillation.

Fig. 1 is a plan view of a coke oven battery equipped with a still for carrying out this invention;

Fig. 2 is an elevation thru the still and hot gas header shown in Fig. 1;

Fig. 3 is a section on the line 3—3 of Fig. 2;

Fig. 4 shows a blower for supplying air to the still; and

Fig. 5 shows a modified form of still.

The coke oven battery 5 is equipped in the usual way with a collector main 6 and cross-over main 7. The gases from the individual ovens pass up thru the uptake pipes 8 and enter the collector main 6 thru the goose-necks 9. At the rear of the battery selected ovens are connected thru additional uptake pipes 10 with the hot gas header 11. By the proper manipulation of valves 12 in the uptake pipes 10 and valves 13 of the usual construction in the uptake pipes 9, the gases from these ovens may be directed either thru the collector main 6 to the usual condensers or thru the hot gas header 11 into the still 14.

Three or four or more ovens, for example as many as five or six or eight, may be connected 60 to the still. It is advantageous to pass the gases from a number of ovens into the still since the gases from a single oven vary in temperature, composition and amount during the coking of a single charge of coal, and by blending the gases from a number of ovens a gas stream of relatively uniform composition, etc. 65 may be obtained.

From the still the gases and vapors pass up thru the baffle tower or saturator 15. The 70 drawings show two sets of baffles 16 and 17 in the saturator. The tar is sprayed into the gases from the spray nozzle 18 situated between the baffles. It flows down over the baffles 16 and is collected at the bottom of the saturator and 75

then conveyed thru the line 19 into the still and enters the still near the end at which the hot gases enter. The baffles may be grids or other suitable baffle means.

5 From the saturator the gases and vapors pass to a preheater 20. In this preheater they are cooled by indirect contact with tar which flows thru the cooling coil 21. The tar is preheated and oils are condensed from the gases. The distillation and the construction and operation of this condenser 20, etc., may be so regulated that the oil which condenses from the gases in this preheater is suitable for sale directly as creosote oil. The oil is drawn off from the preheater into 10 the storage tank 22 or may be run by means of line 22' to decanter 25. From the preheater the gases pass to the condenser 23. This condenser is sprayed with water or ammonia liquor thru the line 24. The condensate and ammonia liquor are drawn off to the decanter 25. The oil, 15 which is carbolic oil, is drawn off into the tank 26. Ammonia liquor is collected in the tank 27. From the condenser 23 the gases pass thru the line 28 to means for the recovery of ammonia, etc. The light oil present in the gases coming from the ovens is largely or entirely burned before the gases enter the still. The gases leaving the condenser 23 may contain light oil from the distillation of the tar in sufficient quantity to warrant treatment of the gases in a light oil absorber.

The still may be five or six feet long and measure two-and-one-half or three feet in cross-section. A smooth cylindrical roll 12" in diameter 20 is rotated at a speed of 900-1200 R. P. M. throws a fine intense spray of tar which substantially fills the entire vapor space of the still and washes all the interior walls of the still and may advantageously be employed for distillation according to this invention.

Such a roll is shown at 29. A motor is indicated at 30. The roll is advantageously rotated in the direction indicated by the arrow. The direction of rotation may be reversed but rotation in the reverse direction increases the power consumption.

The exhauster 31 draws the hot coke oven gases from the selected ovens of the battery thru the hot gas header into the still. In the hot gas header near the still is an opening 32. This opening may be used from time to time to gain access to the header for the removal of any coke which may form and collect in the header. Another opening 33 is provided for the same purpose. Air for combustion of the gases may be drawn into the system thru either or both of these openings or preferably thru another opening provided especially for this purpose. In the drawings the pipe 34, which is attached to the cap on the opening 32, is provided for the admission of air for admixture with the coke oven gases. A valve 35 is provided to adjust the amount of air admitted into the system. The air mixes with the gases in a regulated proportion.

65 The amount of air passing thru the pipe 34 may be regulated by any suitable method. The header 11 may, for example, be maintained under constant suction by the exhauster 31 so that regulated quantities of air can be fed into the system thru line 34 and valve 35 by virtue of the difference in pressures between the header 11 and the atmosphere. Or the air may be supplied under pressure by apparatus such as that shown in Fig. 4 according to which air is supplied thru the pipe 34a from a suitable blower 60 of such

capacity that the desired quantity of air may be had by adjustment of valve 35a and the by-pass valve 61 in the pipe around the blower 60. The combustion gases and unburned coke oven gases, if there be any gases which are not burned, are brought into contact with the fine spray of tar in the still and the heat of these gases effects the distillation. The combustion may take place entirely in the header, which then constitutes a combustion chamber for the coal distillation gases, before the gases enter the still thru the opening 36 or some combustion may take place within the still, a portion of the still itself serving as part of the combustion chamber. The tar spray may actually contact with the flame. The spray is a fine intense spray which exposes a large surface of the tar to the distilling action of the hot gases and the tar is rapidly distilled.

The operation may be controlled to produce a pitch of desired melting point. The flow of tar and air for combustion may be so regulated as to accomplish only partial distillation and the production of a relatively low melting point pitch, for example a pitch suitable for road tars. A pitch of higher melting point may be produced, for example a pitch melting at 350 or 400° F. or higher, by restricting the tar supplied to the preheater 21; or the amount of air fed into the header by means of the pipe 34 may be increased without varying the amount of tar fed to the preheater; or both the tar feed and the air flow may be regulated to give pitch of the desired melting point. The free carbon content of the pitch produced may be regulated by controlling the time during which the material being distilled is maintained at a high temperature and by regulating the temperature. Pitch of high free carbon content may be produced if desired.

The pitch produced is drawn off from the still thru the pitch trap 37 by means of the levelling arm 38. By adjusting the position of this levelling arm the depth of the tar and pitch in the still is controlled. The pitch produced may be treated in any desirable way. It may be blended with other bituminous material or where a high melting point is produced it may be separately collected and hardened. Where, for example, pitch of 350° F. melting point or higher is produced, the pitch may be drawn off into a trough shown at 39 in the drawings and be sprayed with a jet of water from the line 40. The pitch may be chilled and granulated in this way and the hardened pitch is then collected in the bin 41.

Fig. 5 shows a slightly modified form of still 14a. The gases enter from the header 11a in the manner indicated in the previous figures and they leave thru the saturator 15a to condensers, etc. The tar which is sprayed into the gases thru the nozzle 18a in the saturator is partially distilled in the saturator and the residue flows thru the pipe 19a to the still but it enters the still at the end opposite to that at which the gases enter so that the gases and tar flow thru the still in a countercurrent direction. The pitch which is formed is drawn off thru the coke trap 37a into the bin 41a in the manner described in connection with the preceding figures.

Using the gases from three ovens producing 40 tons of coke per day from coal averaging 5% water, and burning sufficient of the combustible constituents so that the gases are raised to a temperature of 1050° C. before they are

brought into contact with the tar, 10,000 gallons of ordinary raw coke oven tar may be distilled to pitch with a melting point of 375 or 400° F., yielding approximately 75% of distillate oil.

5 The temperature, volume and composition of coke oven gases is not uniform from all ovens and the composition of coke oven tar is not uniform so that results may vary over a considerable range.

10 Various modifications may be made and safety devices not shown may be provided to insure safe and efficient operation all within the scope of this invention.

I claim:

15 1. The method of distilling tar which comprises collecting fresh hot coal distillation gases from the ovens or retorts of a coal distillation plant, burning a portion of these gases while they are still at a high temperature after their

20 production, and still contain tar constituents in vapor form, blending the resultant hot combustion gases with another portion of the coal distillation gases which are still hot after their formation so as to produce blended gases of 25 higher temperature than said coal distillation gases, bringing the blended gases into contact with tar so as to distill off oils therefrom and then cooling the resultant gas and vapor mixture to form a distillate containing both constituents 30 originally present in the tar distilled and constituents originally contained in the hot coal distillation gases.

2. The method of distilling tar, which comprises collecting fresh coal distillation gases 35 while they are yet at a high temperature after their formation and still contain tar constituents in vapor form, burning only a portion of the gases and blending the resultant combustion products with the balance of the gases so as to 40 produce blended gases at a temperature above

the temperature at which the coal distillation gases left the ovens, bringing tar into contact with the blended gases so as to distill the tar with the gases while they are at a temperature above that at which they left the ovens, and 5 cooling the resultant gas and vapor mixture so as to form a distillate comprising oils distilled from the tar and oils originally contained in the gases.

3. The method of distilling tar to pitch, which 10 comprises burning a portion of the fresh hot coal distillation gases from a coke oven battery so as to keep the gases above the temperature at which they leave the coke ovens and then distilling tar to pitch by bringing it into contact 15 with the hot gases in the form of a fine intense spray while the gases are still at a temperature above that at which they leave the coke ovens.

4. In combination with a coke oven battery a 20 tar still, means for introducing tar into the still, means for producing a fine intense spray of tar in the gases in the still, means for withdrawing pitch from the still, a combustion chamber, means for collecting gases from ovens or retorts 25 of a coal distillation plant and introducing them into the combustion chamber, means for introducing oxygen into the combustion chamber, and means for conveying gases from the combustion chamber to the still. 30

5. In combination with a coke oven plant a tar still, means in the still for producing a fine intense spray of tar in the gases therein, insulated means for passing fresh hot gases from ovens of the plant to the still and having a 35 portion thereof adapted for the combustion of the fresh hot gases therein, and means for introducing a combustion supporting gas into said insulated means.

GREGORY EDWARD McCLOSKEY. 40
